(57) **CLAIM**

The ornamental design for a makeup lamp, as shown and described.

DESCRIPTION

FIG. 1 is a front, right, top perspective view of the first embodiment of a makeup lamp, showing my new design;
FIG. 2 is a rear, left, bottom perspective view thereof;
FIG. 3 is a front elevational view thereof;
FIG. 4 is a rear elevational view thereof;
FIG. 5 is a left side view thereof;
FIG. 6 is a right side view thereof;
FIG. 7 is a top plan view thereof;
FIG. 8 is a bottom plan view thereof;
FIG. 9 is an enlarged view of detail 9 in FIG. 1;
FIG. 10 is an enlarged view of detail 10 in FIG. 2;
FIG. 11 is an enlarged view of detail 11 in FIG. 4;
FIG. 12 is a front, right, top perspective view of the second embodiment of a makeup lamp, showing my new design;
FIG. 13 is a rear, left, bottom perspective view thereof;
FIG. 14 is a front elevational view thereof;
FIG. 15 is a rear elevational view thereof;
FIG. 16 is a left side view thereof;
FIG. 17 is a right side view thereof;
FIG. 18 is a top plan view thereof;
FIG. 19 is a bottom plan view thereof;
FIG. 20 is an enlarged view of detail 20 in FIG. 12;
FIG. 21 is an enlarged view of detail 21 in FIG. 12;
FIG. 22 is an enlarged view of detail 22 in FIG. 13;
FIG. 23 is an enlarged view of detail 23 in FIG. 13;
FIG. 24 is an enlarged view of detail 24 in FIG. 14;
FIG. 25 is an enlarged view of detail 25 in FIG. 15;
FIG. 26 is an enlarged view of detail 26 in FIG. 18;
FIG. 27 is an enlarged view of detail 27 in FIG. 19; and,
FIG. 28 is an enlarged view of detail 28 in FIG. 19.
